UNITED STATES PATENT OFFICE.

EDMUND CHAMPANE, OF WHITEFIELD, NEW HAMPSHIRE, ASSIGNOR OF ONE HALF TO ALEXANDER F. STOUGHTON, PETER T. STOUGHTON, AND JAMES C. STOUGHTON, OF SAME PLACE.

WRENCH.

SPECIFICATION forming part of Letters Patent No. 545,944, dated September 10, 1895.

Application filed March 2, 1895. Serial No. 540,315. (No model.)

To all whom it may concern:

Be it known that I, EDMUND CHAMPANE, of Whitefield, county of Coos, State of New Hampshire, have invented an Improvement in 5 Wrenches, of which the following description, in connection with the accompanying drawing, is a specification, like letters on the drawing representing like parts.

This invention has for its object the production of a novel wrench, my invention being particularly adapted for what is known as a "carriage-wrench."

My improved wrench consists, essentially, of two jaws, preferably socketed at their acting 10 ends to engage the nut or bolt-head, and the back of said sockets provided with a suitable main adjusting device, preferably a handle having a threaded shank extended through the jaws and fitted with a handle nut at its end 15 at the opposite side of the jaws. The jaws are also provided with a second auxiliary adjusting device in the form of a right and left handed screw, which in the preferred embodiment of my invention is also passed through 20 both jaws beyond the main adjusting device opposite the acting ends of the jaws, suitable means being provided by which to rotate the said auxiliary adjusting device.

My invention further comprehends providing the auxiliary adjusting device, between the two jaws and in line with the axis of the opening between the acting ends of the jaws, with a swivel-handle which may be held in one hand and from an axial bearing about 25 which the wrench and nut or bolt-head may be rotated by the other hand.

The drawing, in perspective, partially broken away, shows one form of wrench embodying my invention.

In the embodiment of my invention shown in the drawing, A A are two preferably like jaws, socketed at a at their acting ends to engage the corners of a nut or bolt-head, and perforated just back of said sockets to receive 30 the shank b of a handle B, said shank at its end opposite the handle B being threaded to receive the handle B', which when turned relatively to the handle B and its shank acts

to move the jaws toward or permits them to be moved from each other. 50

In the preferred embodiment of my invention the jaws A A are extended rearwardly beyond the handles B B', which, with the shank b, constitute one form of main adjusting device, and at their inner ends are again 55 perforated to receive the right and left threaded auxiliary adjusting device C, herein shown as provided at one end with a thumb-piece c, by which it may be rotated in either direction. The right threads of the auxiliary adjuster 60 work in one of the jaws and the left threads in the other, so that rotation of the auxiliary adjuster will cause the rear ends of the jaws to be positively spread or closed toward each other. 65

Between the jaws A A, I have provided the auxiliary adjuster with a cross-pin d, upon the ends of which, at the opposite sides of the adjuster, are swiveled or loosely mounted the handles d'. 70

The operation of the wrench is as follows, viz: The wrench-jaws are placed upon the nut or bolt-head and are screwed together by means of the main adjusting device, thereby obtaining an approximate adjustment or 75 clamping of the jaws upon the nut or bolt-head. This having been done, the operator by turning the auxiliary adjuster positively spreads the jaws at their rear ends and acting about the main adjuster as a fulcrum 80 clamps the acting ends of the jaw tightly upon the nut or bolt-head, so that when the latter is removed it is held tightly in the jaws and may be replaced by the wrench without requiring the nut or bolt-head to be taken in 85 the hands, which is a very desirable feature when the wrench is used in oiling carriages and the like. To remove the wrench from the nut, it is usually sufficient to turn the auxiliary adjuster in an opposite direction, 90 it acting to open the jaws sufficiently to enable the wrench to be easily taken from the nut or bolt-head. For approximate adjustment for nuts or bolt-heads of various sizes rotation of the handle B opens or closes the 95 jaws, the auxiliary adjuster being afterward

operated to clamp the jaws, as described. Assuming the wrench to have been clamped upon the nut or bolt-head, the operator grasps one of the handles d' , and holding the same 5 as a pivot with the other hand rotates the wrench and nut or bolt-head by means of the main adjuster, the handle d' thus forming a swivel-support at the outer end of the wrench to enable the latter to be whirled or rotated. 10 By providing two of the handles, as shown, one of them may also be brought to the outer end of the wrench for use in this manner, and by reason of the auxiliary adjuster being right and left threaded, it matters not what may 15 be the degree of separation of the ends of the wrench-jaws the pin d , upon which the swivel-handles are mounted, is always in line with the axis of the opening, being the acting ends of the jaws. It matters not what the size of 20 the nut may be, the wrench may always be effectively clamped thereupon, and by the use of the combined main and auxiliary adjusters the jaws may be made to hold the nut after it is removed and until it is replaced. 25 My invention is not limited to the particular shape or construction herein shown, for it is evident that the same may be varied without departing from the spirit and scope of my invention.

30 I claim—

1. A wrench containing two jaws, a main threaded adjusting device extended through said jaws and provided at its opposite ends and at the outer sides of the said jaws with handles, rotation of which effects adjustment of the said device, said handles also furnish-

ing means for rotating the wrench, and a right and left threaded auxiliary adjusting device, substantially as described.

2. A wrench containing two jaws, a handle 40 at the outer side of one of said jaws, and having a threaded shank extended through both jaws and receiving upon its threaded end outside the other jaw a second handle, said handles furnishing means by which to adjust the 45 jaws through said device, and also furnishing means for rotation of the wrench, a right and left threaded auxiliary device fitted in said jaws at that side of the main adjusting device opposite the acting ends of the jaws, 50 and a radially extended operating handle for said auxiliary adjusting device and between the said jaws, substantially as described.

3. The combination with two jaws, and a main and a right and left threaded auxiliary 55 adjusting device, of a swivel handle carried by the said auxiliary adjusting device between the said jaws, substantially as described.

4. The combination with two jaws, and a main and a right and left threaded auxiliary 60 adjusting device carried thereby, of the oppositely arranged swivel handles applied to the said auxiliary adjusting device between the said jaws to operate substantially as described.

In testimony whereof I have signed my name to this specification in the presence of two subscribing witnesses.

EDMUND CHAMPANE.
